UNITED STATES PATENT OFFICE.

WILLIAM M. HAINES, OF CHANUTE, KANSAS.

WEB FOOT FOR SWIMMERS.

Application filed February 11, 1924. Serial No. 692,102.

To all whom it may concern:

Be it known that I, WILLIAM M. HAINES, a citizen of the United States, residing at Chanute, in the county of Neosho and State 5 of Kansas, have invented new and useful Improvements in Web Feet for Swimmers, of which the following is a specification.

This invention relates to means for facilitating a person swimming in the water, the 10 general object of the invention being to provide a collapsible member for each foot of the swimmer which will expand and offer resistance in the propulsion stroke of the leg and will collapse on the return stroke.

Another object of the invention is to provide simple means for attaching the device 15 to the foot of the swimmer.

This invention also consists in certain other features of construction and in the 20 combination and arrangement of the several parts, to be hereinafter fully described, illustrated in the accompanying drawings and specifically pointed out in the appended claim.

In describing my invention in detail, reference will be had to the accompanying drawings, wherein like characters denote 25 like or corresponding parts throughout the several views, and in which:

Figure 1 is a side view showing the invention 30 in use upon a foot.

Figure 2 is a view taken from the side opposite to Figure 1.

Figure 3 is a front view.

Figure 4 is a view with the device collapsed.

Figure 5 is a section on the line 5—5 of Figure 2.

In these views, 1 indicates a strap which 40 is adapted to encircle the leg of the swimmer midway the knee and ankle, and to which are attached the vertical straps 2, one at each side of the leg, and the fastening straps 3 are connected with these straps 2. 45 Rods 6 are pivotally attached to the strap 1 and a waterproof sheet 7 is attached to these rods, so as to form an umbrella-like structure. The rods are omitted on the inner

part of the device, so as to not interfere with the swimming movements, and the outer 50 edge of the sheet is attached to the inner strap 2, as shown at 8, so as to prevent this part of the sheet from expanding to any great extent.

From the foregoing, it will be seen that 55 upon the propulsion stroke, the device will be expanded by the water so as to offer the maximum amount of resistance to the passage of the foot of the swimmer through the water, but upon the return stroke the 60 device will collapse, as shown in Figure 4, so as to offer but little resistance to the passage of the foot through the water. Thus, a person may propel himself through the water with great force, due to the 65 resistance offered by the device, one of which is adapted to be placed on each leg of the swimmer.

It is thought from the foregoing description that the advantages and novel features 70 of my invention will be readily apparent.

I desire it to be understood that I may make changes in the construction and in the combination and arrangement of the several parts, provided that such changes fall 75 within the scope of the appended claim.

Having thus described the invention, what is claimed as new, is:—

A device of the class described comprising a ring-shaped strap for encircling a 80 swimmer's leg, side straps connected with the same, means for connecting the side straps with the foot of the swimmer, a waterproof sheet having its top edge fastened to the ring-shaped strap and forming 85 an umbrella-like device, a point of the outer edge of the sheet being connected with a side strap which is adapted to engage the inner side of the leg and ribs connected with the sheet and having their upper ends 90 pivoted to the ring-shaped strap at the front, the outer side and the rear, leaving the inner side of the device free of ribs.

In testimony whereof I affix my signature.

WILLIAM M. HAINES.
